UNITED STATES PATENT OFFICE.

WILLIAM C. GEORGE, OF IOLA, KANSAS, ASSIGNOR OF ONE-HALF TO DANIEL B. D.
SMELTZER, OF IOLA, KANSAS.

BURNER.

1,189,558.

Specification of Letters Patent.

Patented July 4, 1916.

Application filed March 20, 1916. Serial No. 85,430.

To all whom it may concern:

Be it known that I, WILLIAM C. GEORGE, a citizen of the United States, residing at Iola, in the county of Allen and State of Kansas, 5 have invented a new and useful Burner, of which the following is a specification.

The device forming the subject matter of this application is a burner adapted to convert a liquid fuel of any kind into gas, but 10 of peculiar efficiency in connection with distillate oil.

The invention aims to provide a novel valve structure for a device of this type, so constituted that it may be located within a 15 stove, and be subjected to heat, without deterioration or injury.

Another object of the invention is to provide novel means whereby the flames proceeding from the burner tube are adequately 20 spread.

It is within the province of the disclosure to improve generally and to enhance the utility of devices of that type to which the present invention appertains.

25 With the above and other objects in view which will appear as the description proceeds, the invention resides in the combination and arrangement of parts and in the details of construction hereinafter described 20 and claimed, it being understood that changes in the precise embodiment of the invention herein disclosed can be made within the scope of what is claimed without departing from the spirit of the invention.

35 In the accompanying drawings:—Figure 1 shows, in vertical longitudinal section, a device constructed in accordance with the present invention, parts appearing in elevation; Fig. 2 is a top plan view of a combustion device embodying the present invention, parts being broken away; and Fig. 3 shows a cross section taken on the line 3—3 of Fig. 2.

In carrying out the present invention 45 there is provided a base 1 which may be supported on legs 2, the base 1 being equipped with a marginal flange 3. Formed in the base 1 are air inlet openings 4 between which is located a priming trough 5. Up- 50 standing from the base 1 are end walls 6 and 7.

The numeral 8 indicates a portion of the wall of a stove in which the device forming the subject matter of this application is 55 adapted to be mounted.

The invention includes a burner pipe comprising aligned tubular sections 9 and 10. On the inner ends of the sections 9 and 10 is threaded a coupling 11. Disposed within the burner ends of the sections 9 and 10 of the burner pipe is a nipple 12 having a circumscribing rib 14 which is bound between the end walls of the sections 9 and 10 under the action of the threaded coupling 11. The nipple 12 is provided with a bore 15 terminating at its outer end in a valve seat 16. Disposed in the outer end of the section 10 of the burner pipe is a tube 17 having an outstanding flange 18 coacting with the end of the outer section 10 of the burner pipe. Bearing against the outer face of the flange 18 is a packing 19. Threaded onto the section 10 of the burner pipe is a cap 20 which serves to compress the packing 19 against the flange 18, and holds the flange 18 against the section 10 of the burner pipe. 75

Movable longitudinally in the end wall of the cap 20 is a needle valve 21 threaded into the tube 17 and adapted at its inner end to coact with the seat 16 in the nipple 12. The valve 21 may carry a hand-wheel 22. The section 9 of the burner pipe is provided with an upstanding end 52, communicating with a retort 23 disposed above the burner pipe. The burner pipe 9—10 passes through the end walls 6 and 7 of the supporting structure, and the retort 23 rests on the upper edges of the end walls, and is seated in notches in the end walls if desired. As- 80

sembled with the outer end of the retort 23 is a reducer 24 connected with a coupling 25 from which extends an oil pipe 26, the coupling 26 carrying a valve 27. Disposed within the retort 23 is a filler 28 preferably in the form of a solid metal bar and equipped at its ends with radial lugs 29 which, coacting with the retort 23, space the filler 28 from the inner surface of the retort so that the oil will pass through the retort in the form of a comparatively thin sheet. 90

The section 10 of the burner pipe is provided in its top with an opening 30, and the section 9 has a similar opening 31. The openings 30 and 31 are disposed below hollow conical deflectors 32, having internal chambers 33. Across the upper ends of the deflectors extend bridges 34 with which are assembled rings 35 surrounding the retort 23 and upholding spreaders 37. The rings 105 110

35 are held in adjusted positions on the retort by means of set screws 36.

In practical operation, the gas in the burner tube 9—10 burns at the openings 30 5 and 31. The flames thus produced are deflected by the cones 32 onto the spreaders 37 and are caused to shoot outwardly and laterally. Air is admitted through the openings 4 in the base 1, and a hot blue 10 flame is produced. Owing to the fact that the cones 32 are hollow, a minimum amount of heat will be required to raise them to the desired temperature.

Oil admitted to the pipe 26 flows into the 15 retort 23 and is thinned out into a sheet by the action of the filler 28. This sheet of oil is vaporized by the heat emitted at the burner openings 30 and 31. The gas thus produced passes by way of the part 52 into 20 the sections 9 and 10 of the burner pipe.

Especial attention is directed to the fact 25 that the seat carrying nipple 12 is located between the burner openings 30 and 31. By a proper manipulation of the needle valve 21, the flame at the opening 30 may be extinguished, the flame at the opening 31, only, being permitted to burn.

The sections 9 and 10 of the burner pipe, 30 the nipple 12 and the needle valve 21 are made of a good grade of steel, well adapted to withstand a high temperature. Consequently, the valve structure will not deteriorate, although it is exposed to great heat. The construction is such that, by separating 35 the sections 9 and 10 of the burner pipe, the nipple 12 may be renewed at any time should such an operation be necessary.

Having thus described the invention what is claimed is:—

40 1. In a device of the class described, a supporting structure; and a U-shaped member mounted on the supporting structure, the U-shaped member comprising a retort and a burner tube disposed below the retort.

the burner tube being provided with spaced 45 openings; a valve seat in the burner tube and located between the openings; and a needle valve operating in the end of the burner tube, one end of the valve co-operating with the seat, the other end of the needle valve being accessible from a point beyond the burner tube, whereby the flow of fluid to one of said openings may be cut off from a point exterior to the supporting structure. 55

2. In a device of the class described, a supporting structure; a U-shaped member mounted on the supporting structure and including a retort and a burner tube located below the retort, the burner tube comprising 60 separate sections having openings; a coupling uniting the ends of the sections; a nipple in the inner ends of the sections and provided with a circumscribing rib engaged between the end faces of the sections; and a 65 needle valve in one of said sections and co-operating with the nipple.

3. In a device of the class described, a supporting structure; a U-shaped member carried by the supporting structure and including a burner tube and a retort located above the burner tube; a hollow conical deflector disposed below the retort and including a transverse bridge extended across the wider end of the deflector, there being a 75 ring assembled with the bridge, the ring surrounding the retort; and a spreader carried by the ring and disposed above the retort; the burner tube having an opening disposed below the deflector. 80

In testimony that I claim the foregoing as my own, I have hereto affixed my signature in the presence of two witnesses.

WILLIAM C. GEORGE.
